UNITED STATES PATENT OFFICE.

HENRY J. HAIGHT, OF NEW YORK, N. Y.

INCUBATOR.

SPECIFICATION forming part of Letters Patent No. 251,112, dated December 20, 1881.

Application filed November 4, 1880. (Model.)

To all whom it may concern :

Be it known that I, HENRY JANSEN HAIGHT, of the city, county, and State of New York, have invented a new and Improved Incubator or Apparatus for Hatching Poultry; and I do hereby declare that the following is a full and exact description thereof, reference being had to the accompanying drawings, making part of this specification.

10 Figure 1 is a front perspective view of the incubator complete, with some of the shutters open to show the drawer-ways e^2 , upon which the egg-layer drawer A is to be drawn for support, also with the middle legs, M M, for holding the oil-case O, and the lifter L, with its valve accessories. Fig. 2 is a top view of the same, showing especially the valve V, the vertical portions of the cold-air and hot-air passages P' and P², and the skylights of the upper artificial mothers. Fig. 3 is a back view of the same in perspective, showing the artificial mothers especially. Fig. 4 is a perspective view, showing a plan of its construction, a portion of its covering being cut away to 15 show the fresh-air inlet. Fig. 5 is a perspective view of the egg-layer drawer with an egg-layer suspended in it. Fig. 6 is a partial view of the reversed bottom d' of the egg-layer, showing the bolts by which it is kept securely 20 in place, the view being in perspective. Fig. 7 is a view in perspective of the interior of the lamp-chamber D, bringing into view the vaulted casement C, the boiler B, the smoke-pipe or chimney S, and the hot-water-distributing pipes h² h², as well as the returning-watter pipes h⁵ h⁵ and the lamp apparatus. Fig. 35 8 is a sectional view of the boiler B, showing the lamp in its interior and its flame-intensifier n', and outside, showing its distributing and returning pipes and its connection with the opposite reservoirs, R' R'. Fig. 9 is a longitudinal vertical section of the smoke-passage in the casement C, in connection with the interiors j² j² of the boilers. Fig. 10 is a perspective view of the lifting device L of the flame-intensifier. Fig. 11 is a plan of the hot-water reservoirs R' R', the top or cover of the one at the left hand being removed to show the interior construction, showing also the 40 flues of the chimney S in the artificial mothers. Fig. 12 is perspective view of the spring-bolt b' with the parts immediately connected

therewith. Fig. 13 is a transverse vertical section of the entire apparatus.

Like letters designate corresponding parts 55 in all of the figures.

The drawings represent a double incubator with a tier of egg-layers on each side, six artificial mothers, three boilers, &c., the six egg-layers being alike in construction and operation, and the other duplicated parts being alike. I shall describe, therefore, only one of each kind.

The various parts of my improved apparatus are mounted in or on a stationary box supported by a sufficient number of legs, preferably eight for a double incubator, as shown, the upper parts of which form the principal frame-work of the box. It is constructed with two front and two back divisions, the former 65 containing one or more tiers of egg-layers and the latter containing one or more tiers of artificial mothers. A lamp-chamber occupies the middle of the front division; but the box may be made single, with the lamp-chamber at 70 one side, the construction of the hatching apparatus in the front part, of the artificial mothers in the rear part, and of the lamp-chamber being the same as for one-half of the double incubator, including the single lamp-chamber therefor. In a one-tier box, double or 75 single, the artificial mothers may be furnished with either a sloping wire-gauze skylight, V', Fig. 3, or a drawer and balcony.

The arrangement of the front division is as 85 follows: The division is subdivided into two compartments for each egg-layer case, one over the other, the upper one being the egg-layer drawer A, and the lower one including two open cold-air passages, P' P², one open hot-air passage, P², one hot-water reservoir, R', Fig. 11, and one vapor-tray, R², shown separately in Fig. 4.

The egg-layer drawer A is composed of a stationary frame carrying a turning or revolving 95 egg-layer in another frame, a', as shown in Fig. 5. The latter frame is suspended by its journals in bearings or sockets of the outer carrying-frame, a², and is held fast in proper position by a spring-bolt, b', the handle b² of which extends out through the front side of the carrying-frame. This bolt is constructed as shown in Fig. 12. The inner end of the bolt is of larger diameter than the part which works in the outer

frame that carries it, this enlarged end entering a suitable hole in the front part of the turning frame to hold it from turning. Between this enlarged part of the bolt and the inner surface of the carrying-frame a coiled spring surrounds the bolt and acts to force the bolt forward and lock the turning frame. There is also a feather on one side of the bolt, as shown, and a slot in the stationary frame, through which the feather can pass. By turning the knob of the bolt when the same is drawn out, so that the feather is not opposite to the slot, the bolt is held out of the turning frame d ; but when the bolt is turned to bring the feather opposite to the slot the spring acts to force the bolt in, the said feather entering the slot. In the latter position the bolt holds the turning frame fixed. Besides this bolt, the back of the revolving frame is also held by two elastic brackets, b^3 , secured to the inside of the outer frame, on which rest projections b^4 on corner-braces b^5 of the inner revolving frame, as shown in Figs. 5 and 6.

The egg-layer is constructed with a separate bottom, made of a wooden grate, d' , Figs. 5 and 6, laid on narrow strips d^2 , of hard wood or of metal, extending transversely at the ends and in the middle. To fasten this bottom (which has to be reversed in position) to the revolving frame, the tenons on the ends thereof, at the rear side, enter into sockets or eyes d^3 , which project from the above-mentioned corner braces b^5 , and from the middle of the back piece of the outer frame, while the front side is held fast by a sliding bolt in the middle strip entering an eye or socket, d^4 , and, second, by spring-bolts in one of the grate-bars springing into eyes or sockets d^5 at the ends, the spring-bolts being expressly made and adapted for this purpose. The bottom, on its other side, is covered with bolting-cloth, the outer bars of the grate being inserted in its hem d^6 , the cover being loose so as to form troughs between the bars of the grate, in which the eggs are to lie. By this construction, also, the cloth is readily detached for washing. At the time of turning the eggs to their opposite sides the glazed shutters e' , Fig. 1, are opened, the drawer A is drawn out and caused to rest on drawer ways or cleats e^2 , screwed to the inside of the shutters, and another grated bottom, d' , similar to the one which holds the eggs, is carefully laid, with its cloth-covered side downward, on the one which holds the eggs, and secured in that position, by its own tenons and pins, in the frame, which has similar sockets or eyes on both sides. The spring-bolt b' of the drawer is then pulled and fastened back, and the revolving frame is then laterally turned half a revolution and rebolted. The bottom d' , which before held the eggs, is now on top, (the eggs being transferred to the last-applied bottom for support,) and it is taken away. The drawer is then pushed back into the egg-layer chamber.

The lower part of the egg-layer case con-

tains wooden beams f' , Fig. 1, which, crossing upon a wooden bottom, f^2 , form two cold-air passages, P' , at the ends and a hot-air passage, P^2 , between them. These beams also support a vapor-tray, R^2 , Fig. 4, which should be provided with a removable wire cover to prevent the chicks from falling into the tray, and is lined all around with a covered inlet-lining, f^3 , made hollow or tubular, and provided with a number of holes, f , through its outer lateral sides, and through its inner lateral sides with perforations to receive the ends of tubes f^5 , which have long narrow slots or openings in their tops, as shown. Through these holes and tubes fresh air is freely admitted, introduced in the direction indicated by arrows through the waste-water-discharge pipe g^4 , for the purpose of keeping the bolt-cloth covering of the grated bottom cool, and for tempering the hot vapor. These tubes f^5 are attached to and held by the inner walls of the inlet-lining. The tray has near the center an outlet-opening, f^6 , letting into a channel, g^5 , which conveys the discharged water to the discharge-pipe g^4 in either of the horizontal passages, as P^2 . The passages P' P^2 communicate through openings g^7 with open vertical passages P^3 , Fig. 13, interposed between the front and back divisions of the box, and the waste-water pipe g^4 extends down one of these vertical passages to the inclined gutter G, itself provided with a discharge-pipe, g^6 , to carry away the water to any place desired. Into the center of each hot-air passage P^2 valve-apertures g^2 open for discharging the surplus of hot air from the hatching or egg-laying chamber, as shown in Fig. 13, and from this hot-air passage the hot air quickly escapes through the passage P^3 , connected therewith. The upper valve-apertures open into the outer air direct. These valve-apertures are opened and closed by valves V, which are automatically regulated by the temperature of the hatching-chambers themselves.

My improved thermostat or self-regulator for the heat I have made the subject-matter of a separate application for Letters Patent; but I have indicated in Figs. 1, 2, and 3 the mode of connecting the valves therewith, the thermostats being mounted on face-plates E. (Shown in Fig. 1.)

The bottoms of all the passages P' P^2 are covered with sand or thick cloth for the purpose of better retaining the heat for incubation. Under the respective hot-air passages P^2 hot-water reservoirs R' are placed. The construction of those reservoirs is shown in Figs. 11 and 13. Each one is curved laterally, as shown in Fig. 13. It is close or entirely covered, and is best made of tin-lined copper. Inside thereof partition-strips h' h' , Fig. 11, reach from top to bottom and extend from the hot-water pipe h^2 (which is more particularly represented in Figs. 7 and 8) to a point near the opposite side of the reservoir. Narrow covered or tubular passages h^3 bridge or ex-

tend transversely through them, through which 5 passages hot water from the distributing-pipe passes and repasses around the strips, for keeping up a uniform temperature of aqueous heat throughout the reservoir. Also notched brace-partitions h^4 are longitudinally affixed to both the top and bottom of the reservoir, as shown, to keep the same in shape against the expanding action of the hot water. The water-returning pipes h^5 , entering the lamp-chamber D, Fig. 7, and joining the corresponding pipes from the opposite reservoir, as at h^6 , Fig. 8, descend as one pipe to the boiler B, as shown in the figures just referred to. Each reservoir 15 is provided with two short tubes, h^7 , extending vertically through both the top and bottom thereof, and open at both ends. These tubes are located in positions as shown, or thereabout, and their purpose is to conduct heated air from the hatching-chamber beneath up to the valve-apertures g^8 .

The lamp chamber or hall D is lined on top and bottom and all sides with sheet metal, and extends from front to back of the apparatus, 25 between the two parts of a double incubator, as shown, or at one end of a single incubator. One or more boilers, B, are located in the lower part thereof, mounted in the bottom of the same, the lower portions of the boilers being 30 below and outside of the chamber, and thus exposed to the lamps beneath. A vaulted casting or casement, C, surmounts the upper portions of the boilers and incloses a vaulted smoke-passage j' , Fig. 7, which connects with a vertical smoke-pipe or chimney, S, extending up through and out of the lamp-chamber. Each boiler B is constructed with a conical interior surface, j^2 , open at the bottom, and at the top capped with an enlarged top, k^2 , the 35 caps in the several boilers united, forming a continuation of the smoke-passage j' . The space between the outer wall of each boiler and this interior surface or wall, and closed at the bottom, holds the water and forms the 40 boiler proper. The lamps are respectively placed beneath the interior hollow parts of the boilers, and heat the water therein through the interior walls, j^2 . The products of combustion escape through the smoke-passage j' into the 45 chimney S. Each boiler connects with a return water-pipe, h^5 , on one side, as at k^3 , and on the other side has a faucet, k^4 , for discharging its water when desired. These are near the bottom of the boiler. From the top a hot-water 50 pipe, h^2 , extends upward in the lamp-chamber. Each hot-water pipe has two branches or ramifications, j^3 , communicating respectively with the opposite hot-water reservoirs, R', which they supply with water, as clearly shown in Figs. 7 55 and 8. Each double ramification j^3 , or single ramification for single incubators, is provided with a water-supplying box, l', one being shown in Fig. 7, situated high enough to keep the reservoirs connected therewith filled with water 60 by hydrostatic pressure. It is to be kept supplied with sufficient water for the purpose,

and to prevent unnecessary waste by evaporation it may be covered with a close lid, (shown raised in the drawings.) A supply pipe or tube, l', extends from the bottom of the box and 70 enters the ramification to be supplied thereby, and an air-escape tube, l', also enters the same ramification near the supply-tube, extends up through the bottom of the box, and its open end terminates about even with the top of the 75 box. This prevents the collection of air in the ramification. An overflow-pipe, l', extends from near the top of the box inside to a water-discharge pipe, l'. The box may be supported on the return water-pipe h^5 , which leads from 80 the same reservoirs as it supplies.

Adjoining the front end of the casement C a hollow case, j⁶, Figs. 7 and 9, is located, open, at least at the bottom, to allow fresh air to ascend into the casement from the outside, and 85 a little box or vestibule, j⁸, is attached to the front of the said case, situated on the front frame-work of the apparatus, just above the middle legs, M, thereof, so as to be accessible and seen. This box has a glass lid, so that the 90 condition inside may be readily seen, and this lid is raised to get access to the vault and boilers for cleaning out the same.

The chimney or smoke-pipe S has three separate flues, as shown in Fig. 11, the middle 95 flue, j^4 , leading to the heater H for the upper artificial mothers, and the two outer flues, j^5 , carrying the products of combustion again therefrom. A damper, w', controls the entrance of the heated products of combustion 100 into the heater H from the middle flue, the said damper being connected by a connecting-rod with a bell-crank, w², which is suitably connected with a sliding bolt or handle, w³, reaching outside, so that the damper can be readily 105 moved by hand, all substantially as shown in Fig. 11, and thus the heat in this heater is controlled. Any number of heaters H may be supplied in this way.

The lamp apparatus for heating the boilers 110 B is represented in Fig. 7, the oil-case O being represented somewhat out of its usual position to show all parts more clearly. The oil-case holds as many lamps as there are boilers 115 to be heated, the bases of the lamps being soldered to the case, and the upper portions or bodies of the lamps, carrying the burners, being removably screwed or attached to the bases. The case stands on a platform, m', which is provided with grooved truck-wheels m² at the 120 rear end, to roll on slender rails laid on tubes m³, which are supported by sockets m⁴, attached to the middle legs, M M, of a double incubator, or similar legs at one end of a single incubator. Two rods, m⁵, attached to the 125 front bar of the platform in parallel positions, slide in the respective tubes m³, and thus guide and help to support the said platform as it is pushed back or drawn forward by a person holding by the front handle, m⁶. Two stiff 130 rods also extend down from the front of the platform, and unite and rest on a small wheel,

m^7 , Fig. 1, which rolls on the floor, whereby the front end of the platform is fully sustained.

Each lamp is capped with a flame-intensifier, n^1 , consisting of a round copper case of the following construction: It is composed of two parts, as shown in Figs. 8, 9, and 10, the lower part being somewhat conical or rounded to contract its lower end, and the upper part preferably cylindrical. Between the two parts is a circular flange, by which it is supported. The lower part may be perforated with small holes to admit air more freely inside. The upper part is close and quite low, as shown. These cases are, in use, let down around the burners of their respective lamps, to concentrate and intensify the flame ascending through them; but in order to not interfere with moving the lamps forward and back for filling, trimming, &c., they are separately supported and arranged to be raised at any time by a device partly shown in Fig. 7 to indicate its position and mode of suspension, and fully represented in Fig. 10 to show its construction. This holder and lifter consists of a frame, L, composed of two parallel beams, n^3 , connected by a suitable number of cross-bars, n^4 , and provided with sets of opposite inwardly-jutting seats, n^2 , on which the flanges of the respective flame-intensifiers rest and are sustained. Two of the cross bars or rods n^4 have on their respective ends little grooved wheels n^5 , the two at one side of the frame resting on the edges of rounded arms n^6 , having counterbalancing-arms, as shown, and the two wheels at the other side of the frame similarly resting on rounded arms n^7 , which have not or need not have counterbalancing-arms. Each pair of arms is secured to a connecting bar or rod, n^9 , which has bearings in hangers n^8 , screwed or otherwise secured to the lamp-chamber above, and thus the whole apparatus is supported. For raising the frame and the flame-intensifiers supported thereby, the counter-arms of the two arms n^6 are connected by a wire or rod, as shown, and the same rod (or another) extends forward and is connected to one arm of a bent lever, n^{10} , pivoted to one of the middle legs, M, of the double incubator, and provided with a handle, m^8 , all as shown in Fig. 10. On lifting this handle the counter-arms of the arms n^6 are lowered, thereby raising all the arms n^6 and n^7 simultaneously, and consequently raising the frame-lifter L evenly in every part. A reverse movement of the handle m^8 lowers the frame and brings the flame-intensifiers again down around the lamp-burners. The counterweighting of the arms n^6 may be just sufficient to counterbalance the whole device, so that no device will be necessary to hold it in either position, and the raising and lowering of the same is very easy.

By the way of the openings covered by the face-plates E, Fig. 1, oblong vapor-pans W, Fig. 13, may be introduced into the several hatching-chambers. These vapor-pans are supported by suitable rods, as shown, by brackets or

otherwise, as convenient. They serve, of course, to introduce proper moisture into the chambers when needed. The face-plates are covered and protected by glazed doors s^9 , the glass enabling the thermostats to be viewed from the outside, they being mounted on the said face-plates, as before specified.

The back division of the incubator is designed for artificial mothers, to promote the precarious vitality of the feeble chicks fresh from the egg-layers. Their construction is specially shown in Fig. 3. They are constructed in tiers, one above another, in the form of drawers, except the uppermost ones, which are fixed. The tiers are formed as single boxes in single incubators and double boxes in double incubators, the latter being shown in the figure. The upper ones are lighted and ventilated by inclined wire-gauze skylights, V^1 , sustained by hinges, so that they may be raised to open the boxes. All the drawers are provided with sashes at their sides, each sash covered with two sliding panes of glass, and with balconies V^2 outside of them, each formed of wire-gauze, except the bottom, which is of wood. By swinging open the sashes V^2 , or sliding back their panes of glass, the drawers open into the balconies, allowing the young chicks to go out for airing themselves. The balconies are hung by rods V^3 at their inner upper edges on hooks, so that they are readily removed to get access to the drawers. The drawers are covered as to their floors with fine wire-gauze, and that is covered with cloth or other soft material to hold sufficient heat received from the heater H, as shown in Fig. 13. The circulation of the heat in the heater or heaters H is first from the middle flue, j^4 , of the chimney S, thence through the lateral passages v^5 , and finally back to the side flues, j^5 , in the chimney, as indicated by arrows in Fig. 11. The upper mothers are heated thereby from below, while the lower mothers may be heated from above by the same heater; or other heaters may be located below the respective lower mothers.

What I claim as my invention, and desire to secure by Letters Patent, is—

1. The combination of the lamp apparatus, constructed as described, the sliding platform or frame m^1 , and the legs M M, substantially as and for the purpose herein specified.

2. The combination of the egg-layer drawer A, provided with the revolving egg-holding frame a' , with the shutters e' of the hatching-chamber, having supporting cleats or ways e^2 , substantially as and for the purpose herein described.

3. The combination of the revolving egg-layer frame a' , provided with projections or stops, $b^4 b^4$, and the holding-frame a^2 , provided with elastic brackets $b^3 b^3$, and spring-bolt b' , substantially as and for the purpose herein specified.

4. The egg-layer frame provided with a grated bottom, with spaces between the grate-

bars wide enough to admit the whole diameter of the eggs, and covered with a cloth lying loose and "bagging" between the several grate-bars to form troughs for holding the eggs, substantially as and for the purpose herein specified.

5. In combination with the egg-drawer A, the removable grate-bottom d', held in the revolving frame by tenons which enter sockets 10 d³ at one side, and by sliding and spring bolts which enter other sockets, d⁴ and d⁵, at the other side and the ends, substantially as and for the purpose herein specified.

6. The hot-water reservoir R', of arched form, 15 having water-guiding partition-strips h' h' along the middle or highest part, with notches or openings at intervals therein, and other longitudinal partitions, h⁴ h⁴, between the middle strips and the sides of the reservoir, also with 20 notches or openings at intervals therein, substantially as and for the purpose herein specified.

7. The combination of the boilers B, each 25 provided with a hot-water pipe, h², having ramifications j³, communicating respectively with hot-water reservoirs R', all these pipes and the return-pipes h⁵ being located in a single lamp-chamber, D, between the several pairs of opposite reservoirs, substantially as and for the 30 purpose herein specified.

8. In the egg-layer chamber, the vapor-tray R², provided with the hollow inlet-lining f³ for introducing fresh air, the said lining having the holes f⁴, and slotted tubes f⁵, and outlet 35 closed by a plug, f⁶, substantially as and for the purpose herein specified.

9. In combination with the vapor trays R², the separate cold-air and hot-air passages P' and P², with supporting-beams or partitions 40 f' between them, substantially as and for the purpose herein specified.

10. The vaulted casement C, having in its interior a smoke-passage, j', formed of the vaulted tops of the several boilers, and provided with the open-bottomed air-admitting case j⁶, substantially as and for the purpose herein specified.

11. A series of boilers, B B, arranged side by side, each provided with an interior heating-cone, j², having an enlarged top, k², and the

said tops of the several cones being joined together to form one continuous smoke-passage, substantially as and for the purpose herein specified.

12. The water-feed box l', constructed as 55 herein described, in combination with the pipe-ramification j³, the water-supply tube l', and air-escape tube l³, substantially as and for the purpose herein specified.

13. The combination of the boilers B B, the 60 lamp-bearing oil-case O, the flame-intensifiers n', and the means for operating the said flame-intensifiers, all constructed and operating substantially as herein specified.

14. The combination of the flame-intensifiers n', constructed as described, and the lifter L, constructed and operating as set forth, substantially as and for the purpose herein specified.

15. The combination of the oil-case O and 70 the supporting-platform m', provided with truck-wheels m², rolling on tracks which lie on tubes m³, and with rods m⁵, sliding in the said tubes, substantially as and for the purpose herein specified.

16. The lifter L, composed of the beams n³, cross-bars n⁴, grooved wheels n⁵, and provided with seats n² for the flame-intensifiers n', in combination with the eccentrics n⁶ and n⁷, suspended by hangers n⁸, substantially as and for 80 the purpose herein specified.

17. In combination with the chimney S, provided with the inlet-flue j⁴ and exit-flues j⁵, and the damper w', the heating-chambers having heating-passages beneath them, through which 85 the products of combustion pass from the flue j⁴ to the flues j⁵, substantially as herein specified.

18. The combination of the artificial mothers having wire-gauze floors covered with cloth 90 and with a sash-side provided with sliding panes of glass therein, and the balconies having wire-gauze sides, into which the artificial mothers open, substantially as and for the purpose herein specified.

HENRY JANSEN HAIGHT.
